FIG. 1 is a top, front, left side perspective view of a first embodiment of a programmable logic controller system module showing our new design;

FIG. 2 is a front view thereof, the back view being a mirror image;

FIG. 3 is a left side view thereof, the right side view being a mirror image; and,

FIG. 4 is a top view thereof.

The broken line portions of the programmable logic controller system module form no part of the claimed design.
